UNITED STATES PATENT OFFICE.

NAPOLEON DU BRUL, OF CINCINNATI, OHIO.

SCHOOL-SLATE.

SPECIFICATION forming part of Letters Patent No. 225,215, dated March 9, 1880.

Application filed December 8, 1879.

To all whom it may concern:

Be it known that I, NAPOLEON DU BRUL, of Cincinnati, Hamilton county, Ohio, have invented a new and useful Improvement in 5 School-Slates, of which the following is a specification.

My invention relates to an improved hinge or coupling device for those school-slates which consist of two leaves or tablets so connected 10 as to be capable of being folded with equal ease either forward or backward.

My improved coupling device consists, essentially, of a slender metallic rod or wire, which, in connection with suitably grooved 15 and notched slate-frames, serves as a reversible hinge. For this purpose said wire is bent near each end, first at right angles to the central portion, and then bent back to its former direction, thus forming a bayonet-shaped hinge 20 at each end, the middle portion of the wire being parallel to the extremities, as hereinafter described. The thus bent wire having been inserted in the grooves prepared for it is secured in place by the closure of the grooves by 25 means of glued wooden strips or by metallic staples, or both.

In the accompanying drawings, Figure 1 is a perspective view of a folding school-slate embodying my invention. Fig. 2 is a back-edge 30 view of the two frames, and of the coupling-wire and the cleats detached. Fig. 3 represents a modification of my improvement.

A and A' represent the two leaves of a reversible slate whose frames have the customary half-round or convex edges. The opposing frame-edges are grooved longitudinally at a a', 35 and notched transversely at a'', for the recep-

tion of a slender cylindrical rod or wire, B, which is bent near its extremities, b' b'', into the form of a bayonet-like hinge by first bending the wire at right angles to the central portion, and then bending them so that they shall extend in their former direction, said hinge being out of line but parallel with the middle portion, b, of the wire. The thus bent wire 45 having been inserted in the grooves a a' is secured in place by the insertion of glued wooden strips or cleats C, or by staples D, or by both staples and cleats, if desired.

The piece B may be easily and cheaply 50 formed out of round wire, of brass, iron, or other suitable metal, by a single operation of suitable dies.

The above-described illustration of my invention may be changed in non-essential particulars. For example, the coupling-wire may have a greater number of bends, as shown in Fig. 3. The longitudinal grooves may be formed in the face instead of in the edge of 55 the slate-frame.

I claim as new and as my invention—

The double reversible school-slate consisting of a pair of round-edged and longitudinally-grooved and transversely-notched leaves, A' a' a'', and the rod or wire B, bent or formed at 60 the extremities b' b'' into the bayonet-like form shown, the whole being arranged, secured, and adapted to operate substantially as set forth.

In testimony of which invention I hereunto set my hand.

NAPOLEON DU BRUL.
